UNITED STATES PATENT OFFICE.

NEWTON REYNOLDS AND RALPH R. OSGOOD, OF TROY, NEW YORK.

COLLAR-FASTENING.

SPECIFICATION forming part of Letters Patent No. 236,720, dated January 18, 1881.

Application filed July 19, 1880. (No model.)

To all whom it may concern:

Be it known that we, NEWTON REYNOLDS and RALPH R. OSGOOD, of Troy, county of Rensselaer, and State of New York, have 5 jointly invented certain new and useful Improvements in Collar-Fastenings, of which the following is a full, clear, and exact description, reference being had to the accompanying drawings, and to the letters of reference 10 marked thereon.

Our invention has relation particularly to that class of collars (paper, linen, or of other material) which are made detachable from the shirt, and it is applicable to cuffs as well as 15 collars, and to other articles of personal wear, as will be apparent from the following description; and the object of the invention is to make the collar adjustable to different lengths of neckbands and to afford a degree of elasticity in the fastening, so that the collar will give to movements of the neck and resume its 20 normal position whenever the strain is removed. To accomplish this the invention involves an elongated button-hole or slot in each 25 end of the collar or cuff for the reception of the stud or button, and an elastic union between the article and its stud or button, all of which will be hereinafter first fully described, and then pointed out in the claims.

30 In the drawings, Figure 1 is a perspective view, showing a collar detached from its holding-stud upon the shirt-band and provided with elastic fastenings ready to be applied. Fig. 2 is an elevation, showing the collar as 35 held in its customary position by the elastics; and Fig. 3 is a sectional view, showing one end of collar as forced away from its natural position, bringing into play the elasticity of the fastening on one end. Fig. 4 is a perspective view of an ordinary cuff having our 40 improvements applied thereto.

Like letters of reference, wherever they occur, indicate corresponding parts in all the figures.

A is the neckband of a shirt, which may be 45 opened in front or at back, and B is the stud or button secured therein or thereon, after the usual fashion for holding the collar.

C is the collar-band, having at each end an elongated button-hole or slot, d, for securing 50 the collar upon the button B. With these slots it is plain that the collar may be expanded to

its full length upon the button, or it may be considerably contracted, according to the length of the slots. It is intended to make the slots each about an inch in length, so that 55 the entire play will be two inches, and these slots enable one to use one size of collar for shirt-bands varying considerably in length, in consequence of which one size of collar can be made to answer all the purposes of three or 60 four sizes as now ordinarily made, all of which results in a considerable saving to the manufacturer as well as a convenience to the purchaser.

Near each end of the collar-band we attach 65 one end of an elastic loop, a, sufficiently far removed from the inner end of the slot to admit of all the desired play. This attachment may, in the case of paper, celluloid, and such like collars, be made during the process of 70 manufacture and permanent in character. In the case of linen or cloth collars an eyelet-hole, e, may be made at the proper point for the reception of a simple hook, b, upon the end of the elastic a. The free end of the loop is 75 in either case intended to be slipped over the collar-stud, and in the latter case the loop and hook are readily detachable and applicable to other collars. Similar provisions for 80 detachability might, of course, be made in paper and celluloid collars, if desired.

With the improved fastening in place, as indicated in the drawings, the elastic parts hold the collar snugly against the band until extended, and then immediately redraw them to 85 their proper position, thus insuring at all times a perfect-fitting collar, and preventing the tearing of the button-holes as well as accidental unbuttoning.

The set of the collar is greatly improved by 90 use of the elastics and elongated slots, and the attachments add little or nothing to the cost of manufacture.

The ordinary neckties may be employed in connection with a collar having fastening such 95 as shown in the drawings, and, if desired, the free ends of the elastics may be connected with the necktie instead of being looped over the collar-stud, as will readily be perceived.

In the cuff, as shown at Fig. 4, the elastic 100 may be applied the same as upon the collar, the same principles of adjustment obtaining.

It will be found preferable to place the fastenings on the inner side of the cuff out of sight.

In laundered goods the elongated button-holes render it easy to apply the article upon the button, since the walls of the holes (being longer) are more elastic than in common forms.

When constructed in accordance with the foregoing explanations our improved fastenings will be found to admirably answer the purposes and objects of the invention as previously stated; and the device is applicable to all manner of collars and cuffs for ladies' as well as gentlemen's wear. It will be found peculiarly advantageous in all forms of standing collars, since these, when in use, are most affected by motions of the neck of the wearer.

Having now fully described our invention, what we claim as new, and desire to secure by Letters Patent, is—

1. In combination with a detachable shirt collar or cuff having elongated button-holes for the reception of the shirt button or stud, the elastic loops secured near each end of the

article and adapted to pass over the button, to 25 permit the expansion and compel the contraction of the collar or cuff, substantially in the manner shown and described.

2. The herein-described elastic fastenings for collars and cuffs, the same consisting of 30 detachable elastic loops, each provided with a hook for connecting the fastening near each end of the article, and adapted to pass over the central button or stud located in the elongated button-holes *d*, the whole arranged substantially as shown and described, to permit the expansion and compel the contraction of the collar or cuff upon the button, as and for the purpose set forth.

In testimony that we claim the foregoing 40 we have hereunto set our hands in the presence of two witnesses.

NEWTON REYNOLDS.
RALPH R. OSGOOD.
